20 Claims. (Cl. 226—125)

1

The present invention relates to new and useful dispensing apparatus, for dispensing liquids and particularly more or less viscous liquids such as, for instance, lubricants (such as greases and viscous oils, printers' ink, caulking compound etc.), and which relates more particularly to dispensing viscous fluids from an original and relatively thin-walled and inexpensive vendable merchandising container (namely, a container in which the fluid or semi-fluid is originally packed, shipped, stored and sold) preferably by suction applied to an outlet-opening in the bottom of the container while the top of the container is vented to the atmosphere.

One of the objects of the present invention is to suction-dispense such viscous fluids, as, for instance, lubricants, from an original merchandising container, vented at its top, through an opening in the bottom thereof (either with or without the need of removing the lid or top of the container) as for instance, for dispensing such more or less viscous fluids or semi-fluids through an opening in the bottom of a sheet-metal container such as a 15 lb., 25 lb. or 40 lb. (more or less) capacity pail, can or the like, preferably with bail-like carrying-handle, by mounting such sheet-metal container on a dispensing-base or gun-loading pail-base or transfer-base which has a conduit or fluid passage-way therethrough, with one terminal of the conduit generally in the center of the top of the base, and with the other terminal of the said passage-way in or on the side-wall of the base, and with the upper conduit-terminal arranged sealingly to engage the relatively small opening in the bottom of the pail or original container and with the side-terminal of said conduit communicating with a socket-like coupler for making detachable connection with the barrel or reservoir of a grease-gun or the like suction-producing device or for connection with any other lubricant-dispensing pump or the like and means intermediate the dispensing-base and the sheet-metal container for making temporary interlocking engagement between the two, and for firmly securing the container to the base.

Other objects of the present invention will appear from the following description and the accompanying drawings, wherein I have shown, for the purpose of illustrating my invention, forms thereof which are at present preferred, although it is to be understood that the various instrumentalities of which the invention consists can be variously arranged and organized

2

and that the invention is not limited to the precise arrangements and organizations of the instrumentalities as herein shown and described.

In the accompanying drawings, in which like reference characters indicate like parts,

Figure 1 represents a perspective view of one embodiment of the present invention, partly broken away and sectioned.

Figure 2 represents a perspective view of one embodiment of an original merchandising container, of the can phase of the present invention.

Figure 3 represents a perspective view of one embodiment of a dispensing-base of the base phase of the present invention.

Figure 4 represents a fragmentary cross-sectional view of the top and bottom flanges of the dispensing-base, showing a modified form of base construction, in respect to the union or assembly of the top and bottom flanges and the outer side-wall member which unites the top and bottom flanges.

Figure 5 represents a partially vertically cross-section elevational view of a container exemplifying and embodying my invention in a dispensing-container.

Figures 6 and 7 represent a fragmentary sectional view of other forms of construction in follower-plate for use in my container.

Figure 8 represents a vertical cross-sectional view on line 8—8 of Figure 1, showing the container applied to the base, with a hole cut into the bottom of the container and with the periphery of the hole sealed against the base, and with the bottom of the container dished upwardly by the tensioning effect of the interlocking and sealing engagement between can and base.

Figure 9 represents a fragmentary perspective view of the cutter and intake assembly similar to that shown in Figure 8, but on a somewhat larger scale, but without any disc-ejector spring (such as is shown in Figure 8).

Figure 10 represents a vertical cross-sectional view of the base and of the lower portion of the pail or can, similar to that shown in Figure 8 (but on a somewhat larger scale), with the can shown approximately in the position just before the bottom of the can is dished upwardly by the cutter-pressure, and just before the cutters pierce the bottom of the can.

Figure 11 represents a fragmentary cross-sectional view of the base and bottom of the can (similar to that shown in Figures 1, 8 and 10) and of the end of the grease-gun barrel, shown 55 in the position just before the grease-gun barrel

has entered the gun-receiving socket of the base, or in a position just after the grease-gun barrel has been withdrawn from the socket (and with the valve in the base in the closed position).

Figure 11-a represents a cross-sectional fragmentary portion of the end side-wall of the gun-reservoir, and the manner in which the valve-depresser is wedged or forced into the internal groove 50 in the barrel or reservoir.

Figures 12 to 18 inclusive show the various parts and the assembly of the cutter and intake assembly, which may be a part of the base in the embodiment of the invention herein shown, namely:

Figure 12 shows a perspective view of one embodiment of the cutter-supporting intake member, before the clamping lugs thereof have been bent over.

Figure 13 shows a top plan view of this cutter-supporting intake member.

Figure 14 shows a perspective view of the multi-bladed cutter member, itself, with its three cutting points.

Figure 15 shows a plan view of the flat sheet-steel stamped blank for the cutter member, before the cutters thereof have been bent up into a position at right angles to the annulus thereof.

Figure 16 shows a perspective view of the assembled intake member and cutter member,

Figure 17 represents a section on line 17-17 of Figure 16, on an enlarged scale, and

Figure 18 represents a perspective view of one form of disc-ejector spring which may be used in the center of the cutter member, for ejecting the sheet-metal discs which the cutters cut out of the bottom of the sheet-metal can (but without which ejector spring the device may also be used).

Figure 19 represents a vertical cross-sectional view of another embodiment of the present invention, in which the original crimped (or otherwise secured and sealed) lid of the container is removed upon application of the container to the dispensing-base, and in which a separate cover is screw-threadedly or otherwise fastened to the upper bead of the can, and a separate follower-plate inserted into the can before the cover is applied (and in which the original container does not have within it a follower plate, when originally packaged, as in Figures 1 and 8).

Figure 20 represents a fragmentary cross-sectional view of the upper part of the original container, in the embodiment shown in Figure 19, before the crimped lid thereof is removed and before the follower is inserted into the container and before the screw-fastened closure is applied thereto.

Figure 21 represents a perspective view of the discarded tab-type lid, after the tabs have been pried out.

Figure 22 represents a vertical cross-sectional view of the base and the lower part of the container, in another embodiment of the present invention, in which the bottom of the container telescopes over the upper flange of the base, and surrounds it exteriorly, and in which the socket-closing valve is capable of being opened both by the mechanical action of the grease-gun barrel as well as by fluid-pressure incident to the suction of the grease-gun barrel.

Figure 23 represents a fragmentary cross-sectional view through the can-engaging upper flange of the base and through the lower part of the container, similar to that shown in Figures

1 and 8, but on an enlarged scale, better to show the interaction between one of the bayonet-type grooves of the base and one of the bayonet-lugs of the can.

Figure 24 represents a fragmentary cross-sectional view through the can-engaging upper flange of the base and through the lower part of the container, of the form of construction shown in Figure 22, but on an enlarged scale, better to show the interaction between one of the bayonet-type grooves of the base and one of the bayonet-lugs of the can.

Figure 25 represents a plan view of the inner valve disc of the dual-acting valve construction shown in Figure 22.

Figure 26 represents a vertical cross-sectional view of a modified form of construction of base, in which a fluid-pressure actuated valve is placed near the upper intake end of the fluid conduit in the base.

Figure 27 represents a vertical cross-sectional view of a modified form of construction of base, in which a fluid-pressure actuated valve is placed in the conduit of the base intermediate the intake and outlet ends thereof.

Figure 28 represents a vertical cross-sectional view of a modified form of construction of base, in which a fluid-pressure actuated (or suction-actuated) valve is disposed in the gun-receiving socket.

Figure 29 represents a vertical cross-sectional view of a modified form of construction of base, in which a flow-resistant baffle or baffles are placed in the conduit, in lieu of a valve, to prevent the free flow of fluid.

Figure 30 represents a plan type development of the three bayonet grooves of the upper flange of the base, of the forms shown in Figures 1, 3, 8, 10, 19 and 22, with the entire circumference of the flange of the base spread out flat to show the relationship of the three bayonet slots to each other and to show their general contour.

Figure 31 represents a fragmentary perspective view of the bottom of a container showing a spot-welded bayonet-lug member.

Figure 32 represents a fragmentary front elevational view of the spot-welded bayonet-lug member shown in Figure 31, on an enlarged scale.

Figure 33 represents a section on line 33-33 of Figure 32.

Figure 34 shows a development-layout of a modified form of bayonet slot adapted to receive an elongated type of bayonet lug indicated in Figures 35, 36 and 37.

Figure 35 represents a front elevational view of an elongated bayonet lug, at the bottom of a can, which may be spot-welded thereto or which may be pressed into or outward from the bottom of the can (and integrally therewith).

Figure 36 represents a section on line 36-36 of Figure 35.

Figure 37 represents a section on line 37-37 of Figure 35.

In one embodiment of the present invention, the thin-walled original vendable merchandising sheet-metal container, pail or can designated generally by the letter "C" and shown in Figures 1, 2, 5, 8 and 10, is preferably formed with a cylindrical side-wall 1 having its uppermost portion 2 flared outwardly slightly with a beaded edge 96 and having a lid or cover 3 secured to the upper end thereof either by means of the crimped tags 4 or by any suitable means.

The sheet-metal bottom 6 of the container C is initially imperforate and is provided with a

downwardly depending more or less cylindrical flange-like portion 7, which telescopes into the lower end of the cylindrical body 1 of the container C, to a greater or lesser extent, depending upon the axial length of flange 7, and is secured thereto by an interlocking crimped seam 3.

The sheet-metal bottom 6 may have pressed into it, in a downward direction (or in an upward direction), an annular groove 9, to form a doughnut-like ridge or annulus on the outside (or on the inside) of the bottom 6; the outer (or inner) more or less flat or rounded annulus-like surface 10 of which constitutes a seating-surface for making sealing-contact with an annular sealing-gasket or ring 11 (of cork, grease-resistant rubber or composition or other suitable resilient material) carried by the base "B," see Figure 3. The annulus 9 is preferably centered, or approximately centered, in relation to the periphery of the bottom 6.

The annulus 9 also serves to stiffen the center of the bottom 6, so that the circular disc-like portion 12, within the center of the annulus 9, can be more readily cut out or knocked out by the cutting action of the cutters (as in the embodiment herein shown and described) or by any other suitable disc-removal operation. The annulus 9 centers or guides the cutters or knives 13, during the cutting operation, and serves also to stiffen and reinforce the center of the bottom 6 after the disc 12 has been cut out or removed therefrom.

The container may be of relatively thin sheet-steel or "plate," as, for instance, 26 gauge sheet-steel or "plate" (approximately .018 inch thickness) for a 25 lb. pail or 30 gauge for a 10 lb. container or 24 gauge for a 50 lb. container.

In one embodiment of my invention, a plurality (2, 3 or 4, more or less) of circumferentially distributed equidistant bayonet-lugs 14 may be pressed outwardly (or inwardly) from the side-wall 1 of the container C, for interlocking connection with the base B.

Within the container C, near its upper end thereof, is a "follower" 5, which (in one embodiment) is held to the lid 3, while the container C is filled and while the container C is in transit and in storage, prior to its actual use, by means of the screw 93 or the like, in the manner herein-after described, and which is released from the lid 3 when the container is put into use on the base B.

In one embodiment of the base phase of my present invention, illustrated in the drawings, the base "B" may be formed of three members 15, 16 and 17 (see Figure 10), which may be welded to each other or may be interlocked by seams 18 and 19, so as to form a generally unitary construction, in which each member supports and gives rigidity to the other, thereby permitting the three members to be formed (by pressing between dies or by spinning or by rolling, or the like) out of relatively thin sheet-steel as, for instance, 20 or 22 gauge sheet-steel for a base for a 25 lb. container, or other relatively thin sheet-metal and yet maintaining adequate strength and rigidity in the finished base "B."

The upper and lower base-members 15 and 16, respectively, are generally "dish" shaped, while the outer member 17 is a generally hoop-like member which unites the other two, and serves also to stiffen the other two; the members 15 and 16 being arranged with their transverse portions or "bottoms" in juxtaposition and in generally contiguous relation to each other, that is,

with the bottom 20 of the upper member 15 extending downwardly and with the bottom 21 of the lower member 16 extending upwardly, thereby reinforcing each other to give the desired rigidity to the composite of two-ply partition-wall designated generally by the numeral 22.

The cylindrical portions 23 and 24, respectively, of the members 15 and 16, may be either the same diameter or of different diameters, or either or both of them may be "stepped" in several diameters or tapered, in the form of a truncated cone. In the embodiment of the invention herein shown, the upper flange 23 is cylindrical, while the upper diameter of the lower flange 24 is substantially the same as that of the flange 23, and the lower flange tapers outwardly in the form of a truncated cone.

The outer hoop-like member 17 may be made by curving a strip of flat sheet-metal into a hoop-like circle and welding or otherwise securing the ends of the strip to each other, and may be made approximately to fit the diameter or diameters or "steps" or taper of the peripheral or flange-like portions 23 and 24 of members 15 and 16, or it may be spaced away therefrom in an outwardly direction, throughout (or over part of) its extent. In the forms shown, the member 17 is in generally contiguous relation to the sides or flange-like portions 23 and 24 of the members 15 or 16.

In the end-wall or "bottom" 20, a center aperture 25 is formed, and the material from the aperture 25 may be pressed or drawn upwardly to form a short upstanding tube-like cutter-supporting intake-flange or intake member 26, although this tube-like cutter-supporting intake-flange or intake member is preferably formed separately, as shown in the drawings, and spot-welded or crimp-seamed to the aperture 25. The metal around the hole 25 may be pressed down in a downwardly extending annulus 27, forming an annular groove around the tube-like flange 26, for the reception and retention of the resilient and grease-resistant packing-gasket or sealing-ring 11.

From the partition-wall or "bottom" 21 of the lower base member 16, a radial channel 28, of more or less U-shaped cross-section, is pressed in a downward direction, from a point which includes the projected area of the hole 25 (and may also include the projected area of the annulus 27), which channel 28 extends laterally outwardly to the side-wall 24 of the member 16, so as to form a fluid-conducting passageway or conduit extending from the hole 29 (Figure 8) which is ultimately formed in the bottom of the original container, pail or can "C," outwardly to the grease-gun-receiving socket 30 formed in or affixed to the side of the member 17.

From the more or less cylindrical member 17, a circular flange 31 (Figure 10) is drawn or pressed outwardly, in general alignment with the outer end of the passage-way or conduit 28, and preferably turned upwardly at a slight angle, so that the plane of its outer edge will be inclined upwardly slightly from the vertical. The circular center portion of the flange 31 is cut out, and the generally tubular flange 31 is thereafter crimped or flared outwardly as at 33, to overlap and interlock with the inturned flange 34 of the gun-receiving socket 30; the crimped portion 33 of the tubular-drawn flange 31 serving also as a seat for the sealing-gasket 35 (Figure 11) against which the end 36 of the barrel or reservoir 37 of the grease-gun is adapted sealing-

ly to bear, when its screw-threaded end 38 is screwed into the internally screw-threaded portion of the gun-receiving socket 30.

The inner surface 39 surrounding the tubular flange 31 may serve as a valve-seat against which a round shut-off valve 40 is adapted to seat in a direction of the arrow 41, and from which it is unseated in the direction of the arrow 42. The shut-off valve 40 may be carried by a valve-stem or rod 43 which may be guided by a pair of journal brackets 44 and 45 fastened (by spot welding or otherwise) to the wall 20, and the valve is urged into a seating position by helical compression spring 46 which bears against a cross-pin, disc or other abutment 46-a affixed to the stem 43. The other end of the valve-stem 43 carries an operating extension 47, which extends outwardly to a suitable distance, so that it may be contactingly engaged by the multispoked button 48 which is fixedly carried in the front end of the grease-gun barrel or pump-cylinder 37. The button 48 may be held by the spokes 49 which may be held in place by being spread out into an annular groove 50 formed in the inner surface of the outer end of the gun-barrel 37, or may be otherwise secured in the barrel 37, as, for instance, by butt-welding the ends of the spokes 49 as, for instance, by electrical-resistance-heat or "resistance-welding" to the inner side-wall of the barrel 37 by unbending the bowed portions of the spokes 49 to spread the ends thereof into firm contact with the cylinder 37 while welding-current is connected across the spokes and barrel, or by spot-welding the ends of the spokes which have been previously bent parallel to the side-wall of the barrel 37.

Thus, when the gun barrel or pump 37 is screwed into the socket 30, the center portion of button 48 presses the valve-extension 47 inwardly so as to unseat the valve 40 and to permit the lubricant to be drawn out by the manual retraction of the piston 51 within the barrel or cylinder 37, by the manually operable retracting rod or piston rod 52, or by the suction of any other pump-piston.

Instead of the inwardly and mechanically unseating valve 40, I may provide a suction-unseating valve 53, various arrangements of which are shown in Figures 26, 27 and 28, opening outwardly or generally in the direction of the fluid-flow, which may be similarly affixed to and carried by a similar valve-rod 43 and journal or bearing brackets 44 and 45, and seated by a spring 46, but this time against the outer turned periphery 54 of the tubular flange 31, as in Figure 28 or against the inner periphery of the hole 25, as in Figure 26, or against the inner periphery of a valve-hole 55 in the valve-seat wall 56 interposed in the conduit 28, as in Figure 27. Either valve, namely, the inwardly and mechanically unseated valve 40, or the outwardly suction-unseated valve 53, may be placed within the channel 28 or at the opening 25.

Instead of a rod-carried valve (40 or 53), with rectilinear unseating motion, I may use a flap-type hinged or pivoted valve, pivoted at its top, for gravity-seating, or pivoted either at its top or bottom, or at its sides, and seated by any suitable valve-closing spring.

Into the cylindrical side 23 of the upper dish-like base-member 15, and, if desired, also into the co-extensive cylindrical zone of the hoop-like outer member 17, a plurality (two, three or four) of circumferentially distributed and equidistant similar bayonet-grooves or channels 57

are pressed (or otherwise formed) in an outward direction (as in Figures 1, 3, 8, 10, 19 and 23) or in an inward direction (as in Figures 22 and 24), with their outer ends 58 passing through the upper edge 59 of the base member B and with their lower inner ends 60 "blind." See Figure 30.

Each of the bayonet-grooves or channels preferably has a more or less vertical entrance portion 61 of a length such that the traverse of the bayonet-lugs 14 downwardly therethrough is sufficient to cause the cutters 13 fully to pierce and fully to extend through the bottom of the container "C"; the upper edge 59 being so spaced in relation to the ends of the cutters 13 that the extreme ends of the cutters will not quite contact or at least will not pierce the sheet-metal of the bottom of the container "C" while the lower surfaces of the bayonet-lugs 14 are riding on the upper edge 59 of the base B, or are at the plane 20 of the edge 59, and so that the bayonet-lugs 14 must enter the more or less upright portions 61 of the bayonet-channels 57 before the cutters 13 can effectively engage or pierce the bottom of the container "C."

The bayonet-channels 57 have more or less horizontal portions 62, through which the bayonet-lugs 14 pass by rotating the container, after the cutters 13 have been pushed through the bottom of the container, so as to cause the pushed-through cutters circularly to cut through the bottom, or to make a complete circular cut, and thus to make a complete circular hole 29.

The length of the more or less horizontal "cutting" portions 62 of the bayonet-channels 57 depends upon the number of cutters and their arcuate extent. Thus, the amount of turning of the can required for a full cut-out, is that fraction of a turn which will cause the leading edge of one cutter arcuately to travel through the metal (of the bottom) until it meets the initially-pierced hole left behind by the cutter ahead of it. The greater the number of cutters in the circle, or the greater the arcuate width of the base of the cutters, the less turning is required, and, hence, the shorter the portions 62 of the bayonet channels 57. Preferably, the length of the portions 62 of the bayonet-channels 57 is slightly greater than the minimum turning required, so as to give a slight margin of clearance and thus to insure a full circular cut-out.

The bayonet-channels 57 then dip downwardly at a suitable angle as at 63 (see Figures 30 and 34) so as to pull the can downwardly after the hole 29 has been fully cut in its bottom, and thereby sealingly to seat the reinforced and stiffened annular sealing-surface 10 (surrounding the cut hole 29) against the sealing gasket 11 and so as also to seat (or nearly seat) the seamed and beaded bottom edge 64 against the more or less horizontal transverse surface 20 of the upper dish-like base-member 15. The annular portion 65 of the bottom of the can or container "C" (Figure 5) is resilient so as to permit the doughnut-like reinforcing portion 9 (of the bottom 6) and the sealing-annulus 10 thereof, to be displaced to an appreciable extent ($\frac{1}{8}$ " or $\frac{1}{4}$ ", more or less), in a generally axial direction. The upper and lower ends of the inclined portion 63 of the bayonet-channels 57 are so positioned, vertically, in relation to the outer portion of the wall 20 of the base-member 15 which contacts (or is in vertical alignment with) the lower beaded edge 64 of the can, that the relative vertical disposition or spacing of the sealing-surface 10 and of the upper surface of the more

or less resilient sealing-gasket 11, in relation to the upper and lower ends of the inclined portions 63 of the bayonet-channels 57, is such that the annular seating-surface 10 is brought into contact with the upper surface of sealing-gasket 11 before the bayonet-lugs 14 have travelled down the entire length of the inclined portions 63, so that the continued downward inclination of portions 63 causes the annular portion 65 of the bottom 6 of the can "C" to be forced upwardly so as to exert a resilient spring-like force which will maintain effective contact-pressure between the annular seating-surface 10 and the sealing-gasket 11 when the bayonet-lugs 14 have travelled all the way down the inclines 63 and have receded slightly (in an upward direction) into the slightly upturned terminal portions 60 of the bayonet-channels 57; this slight reverse-turn serving as an over-lock, while the upward force exerted upon the whole can "C" (by the upwardly dished and tensioned bottom of the can) tends to keep the bayonet-lugs 14 in the slightly upturned terminal portions 60 so as to prevent accidental unlatching or unlocking of the can "C" from the base "B." The sealing-gasket 11 is also preferably resilient, so as to provide a further "take-up" of any slack or clearance which might otherwise exist in the locked position of the can "C" and base "B."

The basal portions of the can "C" (namely the vertical disposition of the seating-surface 10 thereof and the lower edge 64 thereof and the bayonet-lugs 14 thereof) may be so arranged, proportioned or disposed in relation to each other and in relation to the corresponding partition of the base, that the lower edge 64 of the skirt of the can will seat or "bottom" against the juxtaposed outer peripheral portion of the partition wall 20 of the upper base-member 15, when the can is in its finally "locked" position on the base, or these elements may be so disposed or proportioned in relation to each other, that the lower edge 64 of the "skirt" of the can will not quite "seat" or "bottom" on the base (as indicated in Figure 1), but so that the can will be "bottomed" on the base only on the sealing surface 10 thereof, and so that the can will be held fully "tensioned" between the sealing-surface 10 thereof and the bayonet-lugs 14 thereof (as indicated in Figure 23); the base pushing upwardly on the sealing-surface 10 of the can and pulling downwardly on the bayonet-lugs 14 of the can, with the resiliency of the annular portion 65 of the bottom 6 of the can serving as the tension means to keep the bayonet-lugs pulled upwardly into the upper-turned terminal portions 60 of the bayonet-channels 57 of the base.

I may also so arrange the basal portions of the can "C" (namely, the high of the bayonet-lugs 14 relative to the lower edge 64 of the can) and the can-receiving portions of the base "B" (namely, the height of the lowermost portions 104 of the bayonet-grooves or channels 57 in relation to the outermost annular portion 105 of the upper dish-like member 15 of the base "B"), and the relative height of the sealing-seat 10 in relation to the gasket 11, that the sealing-seat 10 will be firmly seated against the gasket 11 under the influence of the tension created in the annular portion 65 of the bottom of the can, when it is dished upwardly by the sealing pressure between 10 and 11, and yet so as to permit the lowermost edge 64 of the can to seat against the annular portion 105 of the base when the bayonet-lugs 14 have receded slightly into the

slightly up-turned portions 60 of the bayonet-channels 57. This I may do by means of the lateral resiliency or "give" between the bayonet-lugs 14 and the bayonet-channels 57, and by having the bayonet-lugs 14 formed as gradually curved members, instead of defining a sharp or distinct horizontal surface, and by having the portions 62, 63, 104 and 60 of the bayonet-channels 57 also gradually curved in vertical cross-section, so that when the lowermost edge 64 of the can has seated firmly against the annular surface 105 of the base "B," just before the bayonet-lugs 14 glide past the lowermost points 104 of the bayonet-channels 57, the can may, nevertheless, be turned further so as to bring the bayonet-lugs 14 past the lowermost points 104 of the bayonet-channels 57, into the up-turned portions 60 of this bayonet-channel, by causing the bayonet-lugs and the bayonet-channels to "give" slightly in relation to each other, either by the slight inward resiliency of the side of the can at the points of the bayonet-lugs, or by the slight resiliency of the bayonet-lugs themselves and their ability partly to ride up on the sides of the bayonet-channels as though they were to ride out of the channels, until the bayonet-lugs have passed the lowermost points 104 of the bayonet-channels 57. In this manner, I may firmly seat the lowermost edge 64 of the can against the annular portion 105 of the base, while at the same time, the bayonet-lugs have receded into the slightly up-turned portions 60 of the bayonet-channels 57; simultaneously maintaining the seal between 10 and 11 under the influence of the pressure of the up-dished and tensioned annular portion 65 of the can-bottom.

This combination of the outer peripheral seating of the can-edge 64 against the base (as at 105, Figure 10, see also Figure 19), and the tension-sealing of the center-hole 29 of the can against the gasket 11 on the base, may also be accomplished (or augmented) by providing a continuous or an interrupted resilient peripheral annular seat in the portion 15 of the base, so that the lower edge 64 of the can will be firmly "seated" against the base even after the bayonet-lugs 14 thereof have receded upwardly into the slightly up-turned portions 60 of the bayonet-channels 57, without necessarily relying upon any "give" between the bayonet-lugs and the bayonet-channels while the former pass the lowermost points 104 of the latter; at the same time maintaining the seal between the seat 10 and the gasket 11 under the influence of the downward force of the annular portion 65 of the bottom of the can caused by the tensioning of said portion 65 when it is up-dished by contact between the seat 10 and gasket 11.

Such annular resilient "seat" at 105 in the outer periphery of the dish-like portion 15 of the base "B" may be provided by a plurality of circumferentially distributed up-struck bowed leaf-springs (not shown) pressed out of the sheet-metal 20 of the member 15, along its periphery 105, with one end of each such bowed leaf-spring being left integral with the original sheet, and the other end being free to ride and to be supported by the registering portion 106 of the sheet-metal of the lower wall 21 of the base-member 16; such up-bowed leaf-springs being distributed around the periphery more or less equidistantly, and being disposed more or less parallel (or tangent) to the periphery 105 of the base.

I may also form a plurality of generally radially

disposed up-struck leaf-springs from the wall 20, with their inner ends left integral with the wall 20 and with their outer ends free of the wall 20 and bowed upwardly a slight extent so as to form resilient fingers extending a sixteenth ($\frac{1}{16}$) or an eighth ($\frac{1}{8}$) of an inch above the surface 105, so as resiliently to engage the can-edge 64.

Instead of drawing the cutter-supporting intake portion 26 out of the metal of the bottom 20 of the upper base-member 15, I may form the cutter-supporting intake member 26 separately, by drawing the same out of a separate piece of sheet metal, as shown particularly in Figures 8 and 9, and then spot-welding or otherwise securing the base flange 61 thereof to the downwardly extending annulus 27 formed around the hole 25 in the wall 20 of the upper base-member 15, as shown, for instance, in Figures 8, 10, 19, 22 and 26 to 29.

The cutter-supporting member 26 has parts of its cylindrical portion cut away to provide large side-openings 68, with vertical leg-like portions 69 intervening, to support the upper inturned flange 70 (see Figures 12, 13 and 17) upon which rests the flat cutter-annulus 71 with its up-turned cutters 13. In Figure 15 this cutter-annulus, with its cutters, is shown in a flat condition, as pressed out of suitable sheet-steel (capable of being tempered to hold a cutting edge), and before the cutters 13 thereof are bent upwardly, hardened and tempered. The cutting edges 72 of the cutters 13 are beveled to a sharp cutting edge, on the inside, so that the sharp cutting edge is preferably at the outer surfaces of the up-turned cutters 13.

A plurality of notches 73 may be provided in the cutter-annulus 71, for the reception of the crimping and locking lugs 74 carried at the inner periphery of the in-turned flange 70 of the cutter-supporting member 26 (see Figures 9 and 12 to 17). The cutter-annulus 71 is secured to the flange 70 of the member 26 by bending the lugs 74 upwardly and outwardly into the notches or recesses 73 of the annulus 71, and then pressing the so out-turned lugs 74 tightly against the cutter-annulus, as, for instance, shown in Figure 9. If desired, a disc-ejecting spring 75 (as shown in Figures 8, 10 and 16 to 18) may also be secured in the central opening of the cutter-annulus 71, for the purpose of ejecting the discs 12 (see Figure 1) which have been cut out of the bottom of the cans, so as to prevent these discs from piling up on the top of the central opening 106a in the cutter-annulus 71 and in the cutter-support 26. The spring 75 is preferably of a spiral form, so that it can be pressed "flat" into the plane of its outermost and bottom coil 76. This outermost or bottom coil or turn 76 may be fastened beneath the lugs 74, as shown particularly in Figures 16 and 17. Thus, when the can is pressed down over the cutters, the spring 75 is collapsed "flat" so that it will not interfere with the cutting operation, and when the disc 12 has been fully cut out, then the spring forces the disc upwardly into the body of grease, and away from the central hole 106 in the cutter-annulus 71.

The horizontal dimension (as well as the vertical and diagonal dimensions) of the lateral intake openings 68 are sufficiently less than the diameter of the cut-out disc 12, so that the cut-out disc 12 may not enter any of the openings 68 either in vertical position or in horizontal position or in a position diagonally of the holes 68.

The base "B" may be united by interlockingly crimping or rolling together the lower edge of the

base-member 16 and the lower edge of the outer hoop-like member 17, to form either an outwardly extending rolled bead-like seam 19, as in Figures 1, 3, 8, 10, 11, 19, 22 and 26 to 29, or by rolling them inwardly to form a similar inner bead 78, as in Figure 4. The outer hoop-like member 17 may be united with the upper base-member 15, by similarly rolling the upper edges thereof into a bead-like seam 18, which may extend outwardly as in Figures 1, 3, 4, 8, 10, 19 and 23, or may extend inwardly as at 80 in Figures 22 and 24. Likewise, the beads, as, for instance, the upper beads 18 and 80, instead of being hollow round beads, as indicated particularly in Figures 8, 10, 19, 22, 23 and 24, may, instead, be flat, tight-crimped seams, similar to the seam 79 illustrated in Figure 4.

Likewise, instead of the inter-folded or inter-crimped lock-seams 18, 19, 79 and 80, the upper and lower base-members 15 and 16 may be united with the outer hoop-like base-member 17 by welding a continuous line through the two sheets, near their edges, throughout the perimeter, so as to form a fluid-tight seal.

Instead of (or alternative to) the continuous line-weld to unite the dish-like member 15 to the outer hoop-like member 17, or to unite the upper dish-like member 15 to the hoop-like member 17, I may use a series of circumferentially distributed spot-welds at suitable intervals, to unite the contiguous "skirt-like" portions of 15 and 17 to each other, or to unite the "skirt-like" portions of 15 and 17 to each other. Because the transverse walls 20 and 21 of the dish-like members 15 and 16 may be firmly pressed against each other, at the same time that such spot-welding is accomplished, such spot-welding may, alone, provide sufficiently fluid-tight seal between the transverse walls 20 and 21, to retain the more or less viscous fluid in the channel 28 without leakage, and without dissipating the suction created by the pull of the piston 51 of the barrel of the grease-gun (or the like).

The lower edges of the base-member 16 with the outer hoop-like member 17 may be flared outwardly to a radial extent greater than that of the bead 19, so as to form an outer floor-flange of a half inch or so (more or less), and such flanges may then be seamed together by an inter-folded or inter-crimped lock-seam or by welding or otherwise. Such outwardly extending flange will provide a greater floor-contact area for the base and will also permit the feet of the operator to rest on the flange so as to hold the base down on the floor during the application of the can to the base, particularly during the turning required for the cutting operation and the bayonet-locking operation.

The more or less vertical portions 61 of the bayonet-channels 57 may be pressed into the beaded portions 18, 79 and 80 of the upper edge of the base, or they may be similarly pressed into the welded upper edges, where an upper weld-line is used to unite the upper edges of the flange 23 and the member 17 (in place of the beads 18, 79 or 80).

In the embodiments of the invention illustrated in Figures 1, 3, 8, 10, 11, 19 and 23, the upper cylindrical portion of the base (formed of the flange 23 and the upper part of the member 17) telescopically surrounds the lower part of the can "C," while, in the embodiment illustrated in Figures 22 and 24, the bottom of the can telescopes down over (and on the outside of) the top 75 of the base. In the embodiments illustrated in

13

Figures 1, 2, 3, 8, 10, 11, 19 and 23, the inter-folded or inter-crimped lock seam 8 at the bottom of the can "C" is preferably rolled inwardly, so that the outermost diameter of such seam 8 will not extend substantially beyond the outer diameter of the can-body, so as to permit the side-wall of the can to be fitted more closely to the inner diameter of the cylindrical wall 23 of the upper base-member 15, and thereby to permit the use of a bayonet-lug 14 of smaller radial extension.

In the embodiment illustrated in Figures 22 and 24, the seam 8 is disposed entirely on the outside of the main can-diameter, so as to leave the inner diameter of the base-projection of the can "flush" so that it may telescope over and on the outside of the upper part of the base, with a closer fit, and thereby to permit the use of the inwardly extended bayonet-projections 14 of minimal radial extent.

While the bayonet-lugs 14 may be pressed or "drawn" from the 2-ply skirt-like portion 77 of the can (as in Figure 5), by a die-pressing operation, they may also be formed of a separate stamping, or the like, as in Figures 31 to 33, inclusive, and 35 to 37, inclusive, wherein a separate sheet-metal stamping is formed with a bayonet-lug 14 pressed therefrom, with the flange 83 of the stamping spot-welded to the side of the can. By this means a bayonet-lug of greater radial extension may be provided. In either event, however, the bayonet projection 14 is preferably placed at or near the level of the transverse bottom 6 of the can "C," so that the bottom of the can will serve as a radial stiffener to prevent the collapsing of the side of the can by the radial pressure incident to the bayonet-locking of the can to the base.

In Figures 35 to 37 inclusive, a more-or-less elongated bayonet-lug is illustrated. This elongated lug may be used where it is desired to obtain a broader contact surface between lug and bayonet-channel, particularly in the final or locked position of the can and base, where the bayonet-lug rests in the slight upturned terminal portion 60 of the bayonet-channel. In this embodiment, the bayonet channels are made wider in their down-positions, as, for instance, in the portions 61 and 63 thereof, to accommodate the greater circumferential extent of the bayonet-lug, as shown particularly in Figure 34. Such elongated bayonet-lug (as distinguished from the round bayonet-lug) may be either formed separately as in Figures 35 and 37, inclusive, or may be formed integral with the side of the can by being pressed or drawn from the 2-ply skirt portion 77 thereof.

Where the separate bayonet-lugs are used, that is bayonet-lug members formed separately and then welded or otherwise secured to the side of the can, the bayonet lugs are preferably applied at a level so that the lug or the flange 83 thereof will straddle the line of the bottom 6 of the container.

In Figures 22 and 25 a dual or 2-way acting valve is shown for the gun-receiving socket 30, wherein the inwardly opening valve disc 40-a (corresponding to the valve-disc 40 in the exemplifications heretofore described) is perforated as at 85, and provided with a central aperture 86, through which the valve-stem 43 may freely and slidably pass. The valve-stem 43, in this embodiment, is preferably of a diameter slightly less than the diameter of the valve-extension 41, and a second valve-disc 53-a, corresponding generally to the valve 53 in the

14

embodiments heretofore described, is interposed between the valve-extension 41 and the valve-stem 43; the diameter of the disc 53-a being sufficient to cover the apertures 85 in the valve-disc 40-a. The outwardly closing valve-spring 49 (corresponding to the valve-spring 46 in the embodiments heretofore described) is here interposed between the valve-disc 40-a and the guide-bracket 45, while a second spring 87 is interposed between the other side of the guide-bracket 45 and the enlarged inner end 88 of the valve-stem 43, so as to pull the valve-disc 53-a against the valve-disc 40-a.

By this means the passageway 28 may be "unvalved" either by the suction created by the piston 51, or by the action of the button 48, when the barrel of the grease-gun is screwed into the socket 30. Thus, in this form of construction (illustrated in Figures 22 and 25) and the dispensing apparatus of the present invention may be operated either by a grease-gun having a valve-opening or valve-depressing member, like or similar to the member 48 (Figures 10 and 11) or it may be operated by a grease-gun barrel without such member (as, for instance illustrated in Figure 22).

In place of any valve, one or more baffles 89 may be placed in the conduit 28 (as illustrated in Figure 29), preferably in staggered relation to each other, so as to give some resistance to the flow of grease thereby to prevent the free spilling of the grease, when the grease-gun barrel 37 is unscrewed from the socket 30, and before the socket can be closed off by a screw-plug or other closure means.

Likewise a flow-limiting orifice-plate (not shown) may be placed in the conduit 28, to prevent free flow and yet permit suction-induced or pressure-induced flow.

The container "C" may be provided with a follower plate 5 (Figure 5) having an upper dome-like extension 90, pressed upwardly therefrom or formed separately and affixed thereto, to clear the cutters 13 when the follower is in its bottom-most position upon the complete exhaustion of the grease or other contents from the container. The follower 5 preferably also has its main annular portion 91 flared slightly or dished upwardly slightly, towards the center, to conform generally with the upward dishing of the corresponding annular portion 65 of the bottom 6 of the container, when secured in place on the base "B." The dome-like member 90 is completely closed, at its top, and may have a slightly downwardly-dished central portion 92, to give clearance for the end of the screw 93. A perforated disc or band 94 is extended across the downwardly-dished portion 92 of the dome 90, and into the central aperture of the member 94, the screw 93 is screw-threadedly secured so as to permanently hold the follower 5 in its uppermost position, with the upper edge of its cylindrical flange 95 firmly against the upper surface of the lid 3. The lid 3, in this embodiment of the invention, need not be pried loose from the beaded upper edge 96 of the can, but may be left thereon intact, while the grease is being exhausted therefrom through the base "B."

Thus, after the can "C" has been applied to the base "B" in the manner hereinabove indicated (by causing the bayonet-lugs 14 thereof to traverse through the entire extent of the bayonet grooves 57 of the base and thereby cutting a central opening in the bottom of the can and sealing the same to the base, and interlocking securing

15

the can to the base) the screw 93 is unscrewed and removed from the central aperture in the dome-like portion 97 of the lid or cover 3 of the can, thereby creating a vent hole in the top of the lid, so as to permit air freely to enter the container, above the follower. Thereafter, by applying the barrel of the grease-gun to the socket 30, and pulling the piston 51 of the barrel backward, the grease is sucked out of the container through the intake member 26 of the base, through the radial passageway 28 and out through the socket 30, thereby filling the grease-gun barrel.

In place of the "tab" type lid 3, a permanently lock-seamed upper can-end may be provided, so that the can cannot be refilled because the lid cannot be pried loose and replaced.

I may also provide a separate follower 5-a, not included in the can, when the can is "filled" and closed, and a separate lid 98 having a handle 99 and a flange 100 of suitable thickness, through which two or more wing-screws 101 may be extended radially to engage beneath the bead-like upper edge 96 of the can "C." In this embodiment, illustrated particularly in Figures 19, 20 and 21, the original cover 3-a of the container may be without any central dome-like portion 97 and without any central venting aperture or screw, and is pried loose and removed (as in Figure 21) before the container is put to final use, and is replaced by the cover 98, after the follower 5-a has been inserted into the container on the top of the grease. By this construction, a less expensive container may be provided, because the follower 5 need not be duplicated in each container.

As stated above, the dome 90 of the follower 5 or of the follower 5-a, may either be made integral with the follower, as indicated in Figure 19 or it may be made as a separate piece, stamped out of sheet-metal (or otherwise formed) as indicated in Figures 5, 6, 7 and 8, with its flange 107 either spot-welded or line-welded to the overlapped portion of the annular part 91 of the follower, immediately adjacent the center-hole therein, as indicated in Figure 8, or it may be united thereto by a crimped seam as indicated in Figures 5, 6 and 7, wherein either an inturned flange 108 or an outwardly turned flange 109, formed on the dome-element 90, is crimped to and interlocked with the edge of the hole of the follower-annulus 91, as in Figures 5 and 7, or in which the flange 107 is embraced by a crimped-seam formed of a flange 110 drawn from the sheet of the follower, along the center-hole thereof, as in Figure 6.

While in the drawings I have shown the bayonet-projections formed on the side of the can or pail, with the bayonet-channels or grooves formed in the base, I may also, as an alternative embodiment of the present invention, form the bayonet-channels or grooves in the 2-ply skirted bottom portion of the container or pail, and form the corresponding bayonet-projections on the base.

In either form of construction, the tensioning of the bottom of the container or pail, when the opening has been formed therein and when the container or pail has been secured to the base, serves to prevent or retard the unlatching or the disengagement of the container and base, in respect to each other.

The present invention may be embodied in other specific forms without departing from the spirit or essential attributes thereof, and it is

16

therefore desired that the present embodiments be considered in all respects as illustrative and not restrictive, reference being had to the appended claims rather than to the foregoing description to indicate the scope of the invention.

Having thus described my invention, what I claim as new and desire to protect by Letters Patent is:

1. Fluid-dispensing apparatus for dispensing generally viscous fluids from an original vendable merchandising container by suction applied to an outlet-opening formed in the bottom of such container while the top of the container, above the contents thereof, is vented to the atmosphere, said dispensing apparatus including a base having a bottom portion adapted to rest on the floor or like generally horizontal surface and having an upper generally co-axial container-receiving portion for receiving a generally cylindrical original vendable merchandising container and for operatively supporting it, an upper inlet opening disposed generally centrally of said container-receiving portion of the base, a suction-receiving socket on the side of said base, adapted detachably to receive and interlockingly and sealingly to engage the inlet end of the reservoir-barrel of a grease-gun or like suction-producing device, a conduit intermediate said upper inlet opening of the base and the suction-receiving socket of the base, and in communication with each, a generally cylindrical original vendable merchandising container adapted to be disposed in a generally upright position on said container-receiving portion of the base and to be rotated relative thereto in generally co-axial relation thereto, a co-operating interlock on said base and said container arranged to draw said container towards said base, a sealing-ring surrounding said upper inlet opening of said base, the axial distance between the bottom of the container and the lowermost edge of the sidewall of the container, when the container is not attached to the base, being substantially different than the distance between the level of the container-receiving portion of the base and the upper surface of the sealing-ring of the base, so that when the container is drawn to the base by said interlock, the bottom of the container will be dished and tensioned when the bottom of the container and the sealing-ring on the base are pressed into sealing contact with each other by said interlock, and a container-opener for opening the bottom of said container in an area in registration with said upper inlet opening of the base.

2. Fluid-dispensing apparatus, for suction-dispensing relatively viscous fluids such as greases and the like, said dispensing apparatus comprising a base having a bottom portion adapted to rest on the floor or like generally horizontal surface, and having an upper generally co-axial container-receiving portion, said container-receiving portion including a bayonet-flange adapted telescopically to receive the skirted lower end of an original vendable merchandising container, a central inlet opening in said container-receiving portion, a cutter carried by said container-receiving portion in operative juxtaposition to said inlet opening, a suction-receiving socket on the side of said base, a conduit in said base between said inlet-opening thereof and said socket and in communication with each, a generally cylindrical original vendable merchandising container adapted to be vented at its top and to have an outlet opening

17

formed in the bottom thereof; said container having a lower 2-ply flange-like skirt formed in continuation of its side-wall and of its bottom, said skirt being telescoped in relation to said bayonet-flange of the base, and complementary bayonet-means carried by said skirt of the container and said flange of the base, arranged to draw said container toward said base, a sealing-ring surrounding said inlet opening and said cutter on said base, the axial distance between the bottom of the container and the lowermost edge of the skirt of the container, when the container is not attached to the base, being substantially different than the distance between the level of the container-receiving portion of the base and the upper surface of the sealing-ring of the base, so that when the container is drawn to the base by said complementary bayonet-means, the bottom of the container will be dished and tensioned when the bottom of the container and the sealing-ring on the base are pressed into sealing contact with each other by said complementary bayonet-means.

3. Grease-dispensing apparatus for suction-dispensing grease from and through the bottom of a thin-walled and top-vented original merchandising container, said apparatus including a base having a bottom portion adapted to rest on the floor or like generally horizontal surface and having an upper generally co-axial container-receiving portion, an upper inlet opening disposed generally centrally of said container-receiving portion, a suction-receiving socket on the side of said base for sealingly receiving and for making quick-attachable and detachable engagement with the intake-end of the barrel of a grease-gun or like suction-producing device, a conduit inter-connecting said inlet opening and said suction-receiving socket and in communication therewith, a relatively thin-walled original vendable merchandising container adapted to be disposed in a generally upright position on said container-receiving portion and adapted to be vented at its top, a cooperating interlock on said base and the outer periphery of said container arranged to draw said container toward said base, a sealing-ring surrounding said inlet-opening of said base, the axial distance between the bottom of the container and the lowermost edge of the side-wall of said container, when the container is not attached to the base, being substantially different than the distance between the level of the container-receiving portion of the base and the upper surface of the sealing-ring of the base, so that when the container is drawn to the base by said cooperating interlock, the bottom of the container will be dished and tensioned when the bottom of the container and the sealing-ring on the base are pressed into sealing contact with each other by said cooperating interlock, and a container-opener for opening the bottom of said container in an area in registration with said inlet opening.

4. Fluid-dispensing apparatus for suction-dispensing viscous fluids through the bottom of a top-vented thin-walled original vendable merchandising container, including a base having a bottom portion adapted to rest on a floor or like generally horizontal surface, an upper flanged container-receiving portion, an inlet-opening in said container-receiving portion, a suction-receiving socket on the side of said base for sealingly receiving and for making quick-attachable and detachable engagements with the

18

intake end of the barrel of a grease-gun or like suction-producing device, a conduit extending through the lower portion of said base beneath said container-receiving portion thereof and connecting said inlet-opening and said suction-receiving socket and in communication therewith, bayonet-locking means carried by said flange for detachably and interlockingly securing to said base a container on said container-receiving portion thereof, a relatively thin-walled original vendable merchandising container having bayonet means for interlockingly engaging the bayonet-means of the flange of said base, said bayonet-locking means on said flange and said bayonet-means on said container arranged to draw said container toward said base, a sealing-ring surrounding said inlet opening of said base, the axial distance between the bottom of said container and the lowermost edge of the side-wall of said container, when the container is not attached to the base, being substantially different than the distance between the level of the container-receiving portion of the base and the upper surface of the sealing-ring of the base, so that when the container is drawn to the base by said bayonet-means, the bottom of the container will be dished and tensioned when the bottom of the container and the sealing-ring on the base are pressed into sealing contact with each other by said bayonet means, and means for opening the bottom of said container in registration with said inlet-opening.

5. Grease-dispensing apparatus for suction-dispensing viscous fluids through the bottom of a top-vented thin-walled original vendable merchandising container, including a base having a bottom portion adapted to rest on a floor or like generally horizontal surface, a bayonet-flange extending upwardly from said base, an inlet-opening generally in the center of the top of said base, a suction-receiving socket on the side of said base for sealingly receiving and for making quick-attachable and detachable engagement with the intake end of the barrel of a grease-gun or like suction-producing device, a conduit extending through said base from said inlet-opening to said socket and communicating therewith, a cutter carried by said base in operative relation to said inlet-opening, a relatively thin-walled original vendable merchandising container having bayonet means near its lower end for interlockingly engaging said bayonet-flange when in telescoped relation thereto, a generally central aperture-defining deformation in the bottom of the container adapted to receive and to guide said cutter and adapted to stiffen the bottom of the container around the aperture formed by said cutter, said bayonet-means and said bayonet-flange arranged to draw said container toward said base, an annular sealing-seat on the lower surface of said deformation, a sealing-ring surrounding said inlet-opening of said base in registration with said sealing-seat of said deformation, said cutter arranged to open the bottom of the container within said deformation simultaneously with the interlocking engagement between said bayonet-flange and said bayonet-means, the interlocking engagement between said bayonet-means and said bayonet-flange arranged sealing to press said deformation against said sealing-ring by the relative rotation of container and base.

6. Lubricant-dispensing apparatus for suction-dispensing viscous fluids through the bottom of a top-vented thin-walled original vendable mer-

chandising container, comprising a base having a bottom portion adapted to rest on any floor-like or generally horizontal surface and an upper generally horizontally disposed container-rest adapted to support a generally cylindrical container in a generally upright position, an inlet-opening in generally the central zone of said container-rest, a suction-receiving socket on the side of said base for sealingly receiving and for making quick-attachable and detachable engagements with the intake end of the barrel of a grease-gun or like suction-producing device, a conduit extending from said inlet-opening to said suction-receiving socket and in communication therewith, a relatively thin-walled original vendable merchandising container, a follower plate in said container, means for opening the bottom of said container in an area in registration with said inlet-opening of said base, means for detachably securing the container to the base arranged to draw said container toward said base, a sealing-ring surrounding said inlet-opening of said base, the axial distance between the bottom of the container and the lowermost edge of the side-wall of the container, when the container is not attached to the base, being substantially different than the distance between the level of the container-receiving portion of the base and the upper surface of the sealing-ring of the base, so that when the container is drawn to the base by said means for detachably securing the container to the base, the bottom of the container will be dished and tensioned when the bottom of the container and the sealing-ring on the base are pressed into sealing contact with each other by said means for detachably securing the container to the base.

7. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container, an upper inlet-opening in said container-receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, adapted to have a small opening formed in the bottom thereof in registration with said base-inlet, means for opening the bottom of said container in an area in registration with said base-inlet, means for interlockingly securing said container to said base arranged to draw said container towards said base, an annular sealing-seat on the lower surface of the bottom of the container, a sealing-ring surrounding said inlet-opening of said base in registration with said sealing-seat of the container, the axial distance between the level of said sealing-seat on the bottom of the container and the level of the lowermost edge of the side-wall of the container, when the container is not attached to the base, being substantially different than the distance between the level of the container-receiving portion of the base and the upper surface of the sealing-ring of the base, so that when the container is drawn to the base by said means for interlockingly securing the container to the base, the bottom of the container will be dished and tensioned when the annular sealing-seat on the bottom of the con-

tainer and the sealing-ring on the base are pressed into sealing contact with each other by said means for interlockingly securing the container to the base, and means for impeding the free flow of fluid through said base-conduit.

8. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container, an upper-inlet opening in said container-receiving portion of the base, a screw-threaded loading-socket on the side of the base, a conduit intermediate said upper inlet opening and said loading-socket and in communication with each, a relatively thin-walled original vendable merchandising container operatively disposed on the container-receiving portion of said base, adapted to have a small opening formed in the bottom thereof in registration with said base-inlet, means for opening the bottom of said container in an area in registration with said base-inlet, and means for interlockingly securing said container to said base arranged to draw said container towards said base, an annular sealing-seat on the lower surface of the bottom of the container, a sealing-ring surrounding said inlet-opening of said base in registration with said sealing-seat of the container, the axial distance between the level of said sealing-seat on the bottom of the container and the level of the lowermost edge of the side-wall of the container, when the container is not attached to the base, being substantially different than the distance between the level of the container-receiving portion of the base and the upper surface of the sealing-ring of the base, so that when the container is drawn to the base by said means for interlockingly securing the container to the base, the bottom of the container will be dished and tensioned when the annular sealing-seat on the bottom of the container and the sealing-ring on the base are pressed into sealing contact with each other by said means for interlockingly securing the container to the base.

9. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container with its side-portion substantially fully exposed, an upper inlet-opening in said container-receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, said container having a relatively resilient bottom above the lowermost portion of the side-wall thereof, an aperture-defining deformation formed in said bottom in registration with said inlet-opening of the base, means for interlockingly securing said container to said base arranged to draw said container towards said base, an annular sealing-seat on the lower surface of said deformation, a sealing-ring surrounding said inlet-opening of said base in registration with said sealing-seat of said deformation, means for forming an opening in the bottom of the container within said deformation thereof simultaneously with the op-

eration of said means for interlockingly securing said container to said base, said means for interlockingly securing said container to said base being arranged sealingly to press said deformation against said base-inlet by the relative rotation of container and base.

10. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container with its side-portion substantially fully exposed, an upper inlet-opening in said container-receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, said container having a relatively resilient bottom above the lowermost portion of the side-wall thereof, an aperture-defining deformation formed in said bottom in registration with said inlet-opening of the base, means for interlockingly securing said container to said base and for simultaneously forming an opening in the bottom of the container within said deformation thereof and for sealingly pressing said deformation against said base-inlet, by the relative rotation of container and base, said bottom-deformation having an annular downwardly-facing sealing-seat, the axial distance between the level of said sealing-seat of the container and the level of the lower edge of the said side-wall of the container, when the container is not attached to the base, being different from the distance between the level of the container-support of the base and the upper surface of the base-inlet by such an amount as will cause the bottom of the container intermediate said deformation and the periphery thereof to be dished and tensioned by the aforesaid rotational interlocking of container and base and so that such dishing and tensioning of said container-bottom will serve to retard the unlocking of the container from the base and to seal said deformation to said base-inlet.

11. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container with its side-portion substantially fully exposed, an upper inlet-opening in said container-receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, said container having a relatively resilient bottom above the lowermost portion of the side-wall thereof, an aperture-defining deformation formed in said bottom in registration with said inlet-opening of the base, means for interlockingly securing said container to said base, means for forming an opening in the bottom of the container within said deformation thereof simultaneously with the operation of said means for interlockingly securing said container to said base, said means for inter-

lockingly securing said container to said base being arranged sealingly to press said deformation against said base-inlet by the relative rotation of container and base, and means for impeding the flow of fluid from said base-inlet to said loading-socket.

12. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container with its side-portion substantially fully exposed, an upper inlet-opening in said container-receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, said container having a relatively resilient bottom above the lowermost portion of the side-wall thereof, an aperture-defining deformation formed in said bottom in registration with said inlet-opening of the base, means for interlockingly securing said container to said base and, means for forming an opening in the bottom of the container within said deformation thereof simultaneously with the operation of said means for interlockingly securing said container to said base, said means for interlockingly securing said container to said base being arranged sealingly to press said deformation against said base-inlet by the relative rotation of container and base, said bottom-deformation having an annular downwardly-facing sealing-seat, the axial distance between the level of said sealing-seat of the container and the level of the lower edge of the said side-wall of the container, when the container is not attached to the base, being different from the distance between the level of the container-support of the base and the upper surface of the base-inlet by such an amount as will cause the bottom of the container intermediate said deformation and the periphery thereof to be dished and tensioned by the aforesaid rotational interlocking of container and base and so that such dishing and tensioning of said container-bottom will serve to retard the unlocking of the container from the base and to seal said deformation to said base-inlet, and a valve for opening and closing said base-conduit at will.

13. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container with its side-portion substantially fully exposed, an upper inlet-opening in said container receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, said container having a relatively resilient bottom above the lowermost portion of the side-wall thereof, an aperture-defining deformation formed in said bottom in registration with said inlet-opening of the base, means for interlockingly securing

said container to said base, means for forming an opening in the bottom of the container within said deformation thereof simultaneously with the operation of said means for interlockingly securing said container to said base, said means for interlockingly securing said container to said base being arranged sealingly to press said deformation against said base-inlet.

14. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container with its side-portion substantially fully exposed, an upper inlet-opening in said container-receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, said container having a relatively resilient bottom above the lowermost portion of the side-wall thereof, an aperture-defining deformation formed in said bottom in registration with said inlet-opening of the base, means for interlockingly securing said container to said base, means for forming an opening in the bottom of the container within said deformation thereof simultaneously with the operation of said means for interlockingly securing said container to said base, said means for interlockingly securing said container to said base being arranged sealingly to press said deformation against said base-inlet, said means for interlockingly securing said container to said base being arranged to draw said container towards said base, said deformation having a downwardly-facing annular sealing-seat, a sealing-ring surrounding said base-inlet in registration with said sealing-seat of the container, the axial distance between the level of said sealing-seat of the container and the level of the lowermost edge of the side-wall of the container, when the container is not attached to the base, being different from the distance between the level of the container-receiving portion of the base and the upper surface of said sealing-ring by such an amount as will cause the bottom of the container intermediate said deformation and the periphery thereof to be dished and tensioned by the aforesaid interlocking of container and base and so that such dishing and tensioning of said container-bottom will serve to retard the unlocking of the container from the base and to seal said deformation to said base-inlet.

15. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container with its side-portion substantially fully exposed, an upper inlet-opening in said container-receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, said container having a rela-

tively resilient bottom above the lowermost portion of the side-wall thereof, an aperture-defining deformation formed in said bottom in registration with said inlet-opening of the base, means for interlockingly securing said container to said base, means for forming an opening in the bottom of the container within said deformation thereof simultaneously with the operation of said means for interlockingly securing said container to said base, said means for interlockingly securing said container to said base being arranged sealingly to press said deformation against said base-inlet, and means for impeding the flow of fluid from said base-inlet to said loading-socket.

16. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container with its side-portion substantially fully exposed, an upper inlet-opening in said container-receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, said container having a relatively resilient bottom above the lowermost portion of the side-wall thereof, an aperture-defining deformation formed in said bottom in registration with said inlet-opening of the base, means for interlockingly securing said container to said base, means for forming an opening in the bottom of the container within said deformation thereof simultaneously with the operation of said means for interlockingly securing said container to said base, said means for interlockingly securing said container to said base being arranged sealingly to press said deformation against said base-inlet, said means for interlockingly securing said container to said base being arranged to draw said container towards said base, said deformation having a downwardly-facing annular sealing-seat, a sealing-ring surrounding said base-inlet in registration with said sealing-seat of the container, the axial distance between the level of said sealing-seat of the container and the level of the lowermost edge of the side-wall of the container, when the container is not attached to the base, being different from the distance between the level of the container-receiving portion of the base and the upper surface of said sealing-ring by such an amount as will cause the bottom of the container intermediate said deformation and the periphery thereof to be dished and tensioned by the aforesaid interlocking of container and base and so that such dishing and tensioning of said container-bottom will serve to retard the unlocking of the container from the base and to seal said deformation to said base-inlet, and a valve for opening and closing said base-conduit at will.

17. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container with its side-portion substantially fully exposed, an upper inlet-opening in said container-receiving portion of the base, a screw-threaded loading-socket on the side

of the base, a conduit intermediate said upper inlet-opening and said loading-socket and in communication with each, a relatively thin-walled original vendable merchandising container operatively disposed on the container-receiving portion of said base, said container having a relatively resilient bottom above the lowermost portion of the side-wall thereof, an aperture-defining deformation formed in said bottom in registration with said inlet-opening of the base, means for interlockingly securing said container to said base, means for forming an opening in the bottom of the container within said deformation thereof simultaneously with the operation of said means for interlockingly securing said container to said base, said means for interlockingly securing said container to said base being arranged sealingly to press said deformation against said base-inlet, by the relative rotation of container and base, and a follower within said container having a central clearance-dome.

18. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container with its side-portion substantially fully exposed, an upper inlet-opening in said container-receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, said container having a relatively resilient bottom above the lowermost portion of the side-wall thereof, an aperture-defining deformation formed in said bottom in registration with said inlet-opening of the base, means for interlockingly securing said container to said base, means for forming an opening in the bottom of the container within said deformation thereof simultaneously with the operation of said means for interlockingly securing said container to said base, said means for interlockingly securing said container to said base being arranged sealingly to press said deformation against said base-inlet, said means for interlockingly securing said container to said base being arranged to draw said container towards said base, said deformation having a downwardly-facing annular sealing-seat, a sealing-ring surrounding said base-inlet in registration with said sealing-seat of the container, the axial distance between the level of said sealing-seat of the container and the level of the lowermost edge of the side-wall of the container, when the container is not attached to the base, being different from the distance between the level of the container-receiving portion of the base and the upper surface of said sealing-ring by such an amount as will cause the bottom of the container intermediate said deformation and the periphery thereof to be dished and tensioned by the aforesaid rotational interlocking of container and base, and so that such dishing and tensioning of said container-bottom will serve to retard the unlocking of the container from the base and to seal said deformation to said base-inlet, and a follower within said container having a central clearance-dome.

19. Gun-loading apparatus for loading grease-guns and the like with a relatively viscous fluid, comprising a gun-loading transfer-base having

a bottom portion adapted to rest on the floor or generally like horizontal surface and having an upper container-receiving portion adapted operatively to support a container with its side-portion substantially fully exposed, an upper inlet-opening in said container receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, said container having a relatively resilient bottom above the lowermost portion of the side-wall thereof, an aperture-defining deformation formed in said bottom in registration with said inlet-opening of the base, means for interlockingly securing said container to said base, means for forming an opening in the bottom of the container within said deformation thereof simultaneously with the operation of said means for interlockingly securing said container to said base, said means for interlockingly securing said container to said base being arranged sealingly to press said deformation against said base-inlet, and a follower within said container having a central clearance-dome.

20. Gun-loading apparatus for loading grease-guns and the like with a relatively viscous fluid, comprising a gun-loading transfer-base having a bottom portion adapted to rest on the floor or generally like horizontal surface and having an upper container-receiving portion adapted operatively to support a container with its side-portion substantially fully exposed, an upper inlet-opening in said container-receiving portion of the base, a screw-threaded loading-socket on the side of the base, a conduit intermediate said upper inlet-opening and said loading-socket and in communication with each, a relatively thin-walled original vendable merchandising container operatively disposed on the container-receiving portion of said base, said container having a relatively resilient bottom above the lowermost portion of the side-wall thereof, an aperture-defining deformation formed in said bottom in registration with said inlet-opening of the base, means for interlockingly securing said container to said base, means for forming an opening in the bottom of the container within said deformation thereof simultaneously with the operation of said means for interlockingly securing said container to said base, said means for interlockingly securing said container to said base being arranged sealingly to press said deformation against said base-inlet, and a follower within said container having a central clearance-dome.

75

27

base and to seal said deformation to said base-inlet, and a follower within said container having a central clearance-dome.

EDWIN P. SUNDHOLM.
